UNITED STATES PATENT OFFICE.

HUGH H. JOLLIFF AND WARD B. JOLLIFF, OF SPRINGFIELD, OREGON.

GUN FOR DESTRUCTION OF GOPHERS, ETC.

1,410,406.

Specification of Letters Patent. Patented Mar. 21, 1922.

Application filed September 13, 1920. Serial No. 408,807.

To all whom it may concern:

Be it known that we, HUGH H. JOLLIFF and WARD B. JOLLIFF, citizens of the United States, residing at Springfield, in the county 5 of Lane and State of Oregon, have invented certain new and useful Improvements in Guns for Destruction of Gophers, Etc., of which the following is a specification.

This invention relates to improvements in 10 guns for destruction of gophers, moles, and other animals.

An important object of the invention is the provision of a gun which can use an explosive charge to kill gophers, moles, and 15 similar animals.

A further object of the invention is the provision of an animal gun of the above described character which is so constructed as to be easily manipulated, to load and 20 unload an explosive charge.

A further object of the invention is the provision of an animal gun which is simple in construction, yet so durable as to withstand exposure to the atmosphere, and yet 25 function correctly.

Other objects and advantages of the invention will be apparent in the course of the following detailed description.

In the accompanying drawings forming a 30 part of this specification and in which like reference characters designate like parts throughout,

Figure 1 is a side elevation of the animal gun, after it has been operated, and showing 35 its operating parts in cocked position in dotted lines.

Figure 2 is a plan view of the animal gun, showing its operating parts in cocked position.

Figure 3 is a rear end view of the gun.

Figure 4 is a fragmentary cross sectional view showing the gun construction.

In the drawing, wherein for the purpose of illustration, the letter A designates a gun 45 carriage; having the gun B; and hammer C pivotally mounted thereon. A sear D is provided to hold the hammer C cocked; and is capable of operation by a trigger E; in such manner as to fire an explosive charge 50 in the gun B.

The platform or base plate 10 is of such construction as to have all parts of the gun mounted thereon. The gun supports 11 and 12 are rigidly mounted upon the forward 55 end of the base plate 10 as by rivets 13; and have a pin 14 extending laterally through

the gun supports which pivotally carries the gun jacket 15; within which the gun barrel 16 is detachably mounted and is secured thereto by countersunk headed bolts 17 or 60 the like.

It is preferred that the gun B, have the barrel 16 with a bore 18 therein, and cartridge seat 19 adapted to receive the cartridge F. A breech cap 20 is preferably 65 mounted upon the gun barrel as by screw threads 21, and has a firing pin 22 mounted therein of any approved type.

The hammer C is pivotally mounted on supports 25 by a pin 26; and which supports 70 are securely mounted upon the base A as by rivets 27. It is to be observed that in the construction of the hammer C the lower portion thereof has been made relatively narrow as at 28, while the upper portion 75 thereof has considerably more material in it, to add weight thereto, for the purpose of increasing the momentum thereof. The hammer C is so positioned upon the base A that the nose 30 thereof is adapted to contact 80 with the pin 22 to fire an explosive charge. The hammer C is normally forced into contact with the firing pin 22 by the spiral spring 31, which is connected at its forward end to the pin 14, and connected to the hammer C upon the portion 28 above the pivot pin 26.

The sear D is preferably of U-shaped construction, and is pivotally mounted to supports 11 and 12 by a pin 32 having countersunk retaining heads thereon, in such manner that the notches 33 upon the under side thereof are adapted to receive the projections 34 which are transversely placed upon the portion 28 of the hammer C, for holding 95 the hammer C in a cocked position.

The trigger E is pivotally mounted upon a support 35 as by a pin 35^a; and which support is rigidly mounted upon the base A as by rivets 36. The trigger E is provided 100 upon its lower edge with the tumblers 37, which are positioned thereupon immediately below the sear D; that upon the pivotal movement of the trigger E they will engage the under surface of the sear D for rocking 105 the same, to disengage the hammer C, and fire the explosive charge. Since the gun is adapted primarily for the purpose of shooting gophers, or the like, a rod 40 is pivotally mounted by a pin 41 upon the upper end of 110 the trigger E and extends parallel with the gun barrel through the bracket 42 mounted

thereupon, in such manner, that the hook 43 is positioned in front of the muzzle of the gun B. However it is to be noted that the hook 43 is so curved that the bullets from 5 an explosive charge will not injure the same.

In operation, some article of food is placed upon the hook 43; the gun B is then tipped upon its pivot in such manner as is shown by the dotted lines in Figure 4 of the drawing. The breech cap 20 is then unscrewed and an explosive charge is inserted into the barrel. After the breech cap has been replaced the gun is replaced in its normal position, and the hammer C tilted back until 10 the projections 34 engage the notches 33 of the sear D to hold same in a cocked position. When the gopher or other animal exerts a push or pull upon the rod 40 in its attempt to detach the article of food thereon, 15 it will rock the trigger until the tumblers thereof engage the under surface of the sear, thus raising the same and disengaging the projections of the trigger, and firing the explosive charge. Since the animal is positioned directly in front of the muzzle of 20 the gun it can readily be seen that it will receive the explosive charge and be killed.

Changes in detail may be made without departing from the spirit of the invention.

30 We claim:

1. In a gun, the combination, of a base, supports mounted upon said base, a gun barrel pivotally mounted between said supports, a breech cap for said barrel, a firing pin, 35 a hammer pivotally mounted upon said base, a sear pivotally mounted upon said barrel supports for engaging the hammer, and means for operating said hammer to discharge an explosive charge, said means operable from the forward part of the gun.

2. In a gun, the combination, of a base plate, supports rigidly mounted upon said base plate, a gun barrel, a jacket for said barrel pivotally connected to said supports 45 for permitting loading and unloading of said barrel, a breech cap detachably mounted upon said gun barrel, a firing pin, a hammer pivotally carried by said base plate, a spring connected to said supports and normally urging the hammer into engagement 50 with the firing pin, a sear pivotally carried by said supports to hold said hammer in a cocked position, and means for operating said hammer to fire an explosive charge, 55 said means operable from the muzzle end of the gun.

3. In a gun, the combination, of a base

plate, supports rigidly mounted upon said base plate, a gun barrel, a jacket for said barrel pivotally connected to said supports 60 for permitting loading and unloading of said barrel, a breech cap detachably mounted upon said gun barrel, a firing pin, a hammer pivotally carried by said base plate, a spring connected to said supports and normally urging the hammer into engagement 65 with the firing pin, a sear pivotally carried by said supports to hold said hammer in a cocked position, a trigger pivotally carried by said base and means for operating said 70 trigger to unseat the sear and fire an explosive charge.

4. In a gun, the combination, of a base plate, supports mounted upon said base plate, a gun barrel pivotally connected to 75 said support, a U-shaped sear pivotally connected at its ends to said support and having notches intermediate its extremities, a hammer pivotally carried by said base plate having projections thereon adapted to fit within the notches in said sear for holding the hammer in cocked position, means tending to force said hammer toward said gun, and means for releasing said hammer to fire an explosive charge.

5. In a gun, the combination, of a base plate, supports pivotally mounted upon said base plate, a gun barrel, a jacket for said barrel pivotally connected to said supports for permitting loading and unloading of 90 said barrel, a breech cap detachably mounted upon said gun barrel, a firing pin, a hammer pivotally carried by said base plate, a spring connected to said supports and normally urging the hammer into engagement 95 with the firing pin, a U-shaped sear pivotally connected at its ends to said supports, and having notches therein to engage said hammer to hold the same in cocked position, a trigger pivotally carried by said base and 100 means for operating said trigger from the forward end of said barrel to release the hammer and fire an explosive charge.

6. In a gun, the combination of a base, supports mounted upon said base, a gun barrel pivotally carried by said supports, a hammer pivotally mounted upon said base, a sear pivotally mounted upon said barrel supports for engaging the hammer, and means for disengaging said sear for operating said 105 hammer.

HUGH H. JOLLIFF.
WARD B. JOLLIFF.
